JOHN L. CREVELING, OF NEW YORK, N. Y., ASSIGNOR TO SAFETY CAR HEATING AND
LIGHTING COMPANY, A CORPORATION OF NEW JERSEY.

ELECTRIC REGULATOR.

1,118,333.

Specification of Letters Patent. Patented Nov. 24, 1914.

Application filed March 18, 1910. Serial No. 549,575.

To all whom it may concern:

Be it known that I, JOHN L. CREVELING, a resident of New York, in the county and State of New York, have invented certain new and useful Improvements in Electric Regulators, as set forth in the annexed specification and drawing, forming a part thereof.

My invention pertains to that class of devices or apparatus known as electric regulators adapted to regulate the current in an electric circuit or the voltage impressed thereupon.

My invention has for its particular object to provide an electric regulator which will automatically govern a circuit so as to produce predetermined conditions therein automatically, for example, to hold the voltage upon a circuit constant regardless of fluctuations in voltage at the source of current supplying said circuit.

The drawing is a diagrammatic representation of a translation circuit supplied from a source of variable electro-motive force and my regulator is shown in connection with the translation circuit and so arranged as to hold the voltage upon the same constant throughout the above mentioned variations in voltage upon the supply circuit.

In the drawing 1 represents any suitable source of current subject to variations in electro-motive force as, for example, a storage battery which may be connected in any desired manner to a suitable charging circuit (not shown). From the positive side of the storage battery the main 2 is carried to the lamps or translating devices indicated at 3 from which the main 4 is carried to one side of the regulator 5 from which return to the battery is made as by main 6. Current flowing from the main 4 may be considered as entering the conducting member or plate 7, mounted upon the insulating base 8, and in electrical communication with the regulating element 9, the regulating effect of which is varied by variations in pressure exerted thereupon as, for example, a pile of carbon disks or contacting electrodes. The disks 9 are held in place as by insulating

tubes 10 carried by the rods 11 supported by the base 8. The opposite end of the upper pile of disks 9 is in contact with the conducting member 12 carried by the screw 13 threaded into the insulating bushing 14 carried by the yoke 15. The position of the

conducting member 12 may be governed by the screws 13 which may be locked in position as by the nut 16. The upper and lower screws 13 are electrically connected as by means of the wire 17.

18 represents a rod of brass or other non-magnetic material provided with the adjusting nuts 19 and 20. The nut 20 has a substantially spherical portion which is in contact with the yoke 15 in the manner indicated so as to allow a slight rocking motion thereupon to equalize the pressure between the two sets of disks 9. The spring 21 surrounds the rod 18 and normally presses the yoke 15 against the nut 20; therefore, it will be obvious that pull in a right-handed direction exerted upon the rod 18 will tend to compact the disks 9 in such manner as to reduce the resistance thereof and that the voltage upon the translation circuit may be regulated by varying the pull upon the said rod 18.

22 represents an iron frame supporting the insulating base 8 and the parts of the regulator attached thereto and held in any suitable position as by bosses 23 and screws 24. This magnetic frame 22 is provided with a central tube of non-magnetic material indicated at 25 which holds in place the coils 26 and 27. The rod 18 passes through a slip hole 28 in the base 8 and is connected with a core of iron or other magnetic material indicated at 29 which is provided at its opposite end with a brass rod 30 passing through the iron plug 31 which is screwed into the frame 22 and locked in a fixed position as by jam nut 32. The rod 30 passes through a slip hole 33 in the plug 31 so as to shorten the contact surface at 34 and thus facilitate alignment. If one of the coils, for instance, coil 26 be energized lines of force will be caused to pass across the air gap 35 in a well-known manner and tend to draw the core 29 toward the plug or core 31 and thus compress the disks 9.

36 is an extension of the frame 22 provided with a lever 37 made of non-magnetic material and pivotally carried by said extension.

38 is a rod passing through the lever 37 and provided with the nut 39 adapted to compress the spring 40 against the lever 37 so as to press the said lever against the end of the rod 30 and thus tend to reduce the pressure upon the disks 9. The nut 41 limits

the travel that may be given to the rod 30 by the spring 40. The main 4 is connected with one end of the coil 26 as by wire 42 the other end of said coil being carried as by wire 43 to the resistance 44 which is connected with the main 2 as by wire 45.

46 represents a small resistance varying element as, for example, a pile of contacting electrodes such as carbon disks which are in electrical communication with the insulated bracket 47 and held in place as between insulating rods 48. The other end of the pile 46 is in contact with the conducting member or disk 49 carried by the adjustable screw 50 which is carried by the lever 51 normally drawn as by spring 52 adjustable as by screw 53 in such direction as to tend to lessen the pressure upon the pile 46. The limit of motion that can be given the lever 51 by the spring 52 may be adjusted as by the screw 54. The insulated bracket 47 and screws 53 and 54 are carried upon a plate of non-magnetic material indicated at 55 which is carried upon the pole pieces of iron or other magnetic material 56 which are united to the usual core (not shown) of the electromagnet 57 as by means of screws or studs 58.

59 is a stationary core of magnetic material carried by the plate 55 for the purpose of reducing the air gap between the pole pieces 56. The lever 51 is supported by the pivot or shaft 60 carried by and free to revolve in the depending bracket 61. The shaft 60 has fixed thereto a spool or form of non-magnetic material 62 carrying the coil 63 also of non-magnetic material which may be in series with the winding of the electromagnet 57 and both the coil and the winding are connected across the translation circuit as by wires 64 and 65. It will thus be obvious that any motion given to the spool 62 will turn the shaft 60 so as to swing the lever 51 and vary the pressure upon the pile 46 and disks 46 and so wind the coil 63 and the electromagnet 57 that current flowing therethrough will cause the spool 62 to tend to turn in a right-handed or clock-wise direction and thus increase the pressure upon the pile 46 and decrease the resistance of the pile 46 in a well-known manner. As this construction is well-known in the manufacture of electrical instruments, further description of details is omitted. The wire 66 is carried from the wire 43 to the insulated bracket 47 and the conducting member 49 is connected with one end of the coil 27 as by means of wire 67, the other end of said coil 27 being connected to the wire 42 as by wire 68. It will thus be obvious that the resistance 46 and the coil 27 are in series with each other in a circuit in shunt across the coil 26 and that any current taken by this circuit will weaken the current in coil 26 and that this weakening effect may be increased by

winding the coil 27 in such manner that its magneto-motive force is opposed to that of the coil 26.

The practical operation of my improved regulator is substantially as follows: Current will flow from the battery 1, or other source through the main 2 to the translating devices 3 and return through main 4, upper regulating means or disks 9, wire 17, lower disks 9 and main 6 back to the source and the voltage impressed upon the translating devices 3 will accordingly vary as the pressure upon the disks 9 is varied. Current will also flow from the main 2 through wire 45, resistance 44, wire 43, coil 26 and wire 42 to the main 4. This current will cause the core 29 to be drawn toward the core 31; and I so adjust said core and nuts 19 and 20 that the air gap 35 shall be small so as to exert a heavy pressure upon the disks 9. Current will also tend to flow from the wire 43 through the wire 63, insulated member 47, pile 46, conducting member 49, wire 67, coil 27 and wire 68 to the wire 42, and this current may be governed by the resistance 46 which will be altered upon changes in pressure thereupon in a manner as will hereinafter more fully be brought out. Current will also flow from the main 2 through the wire 65, coil 63, winding of the magnet 57 and wire 64 to the main 4 and this current will be a function of the voltage across the translating devices 3. This current flowing through coil 63 and magnet 57 will tend to turn the spool 62 and shaft 60 in a right-hand direction and tend to cause the lever 51 to compress the pile 46 and reduce the resistance thereof and thus increase the current flowing therethrough, said action being opposed by the adjustable spring 52. If the voltage at the source be such that the voltage impressed upon the translating devices 3 is at, or below, the normal, it will be desired that the resistance in circuit with the translating devices 3, that is, the resistance of the disks 9, shall be very low or, under some conditions, a minimum and under these conditions I, therefore, adjust the spring 52 by means of the screw 53 so that there is little, if any, pressure exerted by the lever 51 upon the pile 46 so that the resistance thereof is very high and very little, if any, appreciable current is shunted away from the coil 26 by the circuit containing the pile 46 and, therefore, the coil 26 will exert a heavy pull upon the disks 9 through the core 29, and cause said disks to have a very low resistance. If now the voltage across the translating devices for any reason tends to rise, the increase in current flowing through the coil 63 and electromagnet 57 will cause an increase in pressure upon the pile 46 which will cause an increase in the current shunted away from the coil 26 through the pile 46 and coil 27. The coil 27 being wound so as

to oppose the coil 26 a slight change in the current in this circuit will make a considerable change in the resultant magneto-motive force of the coils 26 and 27 and a considerable variation in the pressure exerted upon the disks 9. Therefore, a slight increase in voltage across the translating devices 3 will cause the resistance 46 to lower and the pressure upon the disks 9 to lessen and increase the resistance thereof so as to hold the voltage across the translating devices 3 substantially constant throughout wide ranges in variation across the battery terminals. If now the voltage shall fall somewhat the spring 52 will cause the resistance 46 to be increased and the pressure upon the disks 9 increased and their resistance lowered in such manner as to tend to hold the voltage across the translating circuit constant as may be readily seen from the above description.

Having thus described my invention that which I consider as novel and desire to protect by Letters Patent is as set forth in the following claims:

1. An electric regulator comprehending a variable resistance, means for varying said resistance by exerting pressure thereon comprising a coil and a movable core therefor; together with a fixed core adjustable in relation thereto, and means for varying the magnetic flux of both cores, included in a circuit in shunt across said coil.

2. An electric regulator comprehending a variable resistance, means for varying said resistance by exerting pressure thereon comprising a coil and a movable core therefor; together with a fixed core so related to the movable core as to form an air gap, and means for varying the attraction between said cores, included in a circuit in shunt across said coil.

3. An electric regulator comprehending a variable resistance, means for varying said resistance by exerting pressure thereon comprising a coil and a movable core therefor; together with a second coil and fixed core therefor adjustable in relation to said movable core, and a second variable resistance in circuit with the second coil and adapted to produce a variable magnetic flux upon both cores.

4. An electric regulator embracing a variable resistance, means for varying said resistance including a movable member of magnetic material and a fixed member of magnetic material in adjustable relation; together with a plurality of coils for effecting the attraction between said members, and means in series with one of said coils and in shunt to another for varying said attraction.

5. An electric regulator embracing a variable resistance, means for varying said resistance including a movable member of

magnetic material and a fixed member of magnetic material in adjustable relation; together with coils for effecting the attraction between said movable and fixed members; a circuit including a second variable resistance in series with one of said coils and in shunt to another, and electromagnetic means for varying the resistance of said circuit.

6. An electric regulator embracing a variable resistance provided with circuit connections for placing it in the circuit to be regulated; in combination with means for varying said resistance including a movable member of magnetic material and a fixed member of magnetic material in adjustable relation; two coils for affecting the magnetic flux between said members; a circuit including a second variable resistance in series with one of said coils and in shunt to the other, electromagnetic means for varying said resistance.

7. An electric regulating device embracing a variable resistance, electromagnetic means for varying said resistance by pressure comprising two cores and two coils, and a circuit including a second variable resistance in series with one of said coils; in combination with independent circuit connections between said resistances and coils and the circuit to be controlled.

8. An electric regulating device embracing a variable resistance having circuit connections included in the circuit to be regulated, electromagnetic means, for varying said resistance by pressure, embracing two cores; one movable and the other fixed, and coils for producing variable magnetic flux upon said cores; a circuit including a second resistance in series with one of said coils and in shunt to the other, and independent means for varying said second resistance.

9. Means for regulating an electric work-circuit comprising regulating means responsive to variations in pressure and inserted in said circuit with the work to be performed; means for creating pressure on the regulating means including a coil connected across the work-circuit; a second coil in shunt around the first coil; a second regulating means responsive to variations in pressure in series with the second-named coil; and means for creating pressure upon the second-named regulating means connected across the work-circuit.

10. Means for regulating an electric circuit comprising a resistance variable in proportion to the pressure imposed thereon; means for variably imposing such pressure upon said resistance, including a coil and a core operated thereby; a second coil wound to oppose the action of the first-named coil and connected in shunt around the latter; a second pressure responsive means in series with the second-named coil; and electro-

18,333

magnetic means for imposing pressure upon the second pressure responsive means.

11. An electric regulator for regulating an electric circuit comprising a resistance variable in accordance with the pressure imposed thereon; two separated cores arranged in alinement therewith, and two coils surrounding the same and wound to oppose each other for varying the pressure upon said resistance; means operatively connecting the cores to the resistance; interconnected circuits for the two coils, so arranged that one of the coils is connected in shunt

5 to the resistance and the other coil is connected in shunt to the first-named coil; and 15 a second resistance variable according to the pressure imposed thereon arranged in one of the coil circuits so as to vary the action of both coils; and current-controlled means for varying the pressure imposed 20 upon said second resistance.
